UNITED STATES PATENT OFFICE.

LEON SERPOLLET, OF PARIS, FRANCE, ASSIGNOR TO LA SOCIÉTÉ DES GÉNÉRATEURS À VAPORISATION INSTANTANÉE, (SYSTÈME LEON SERPOLLET,) OF FRANCE.

TUBE FOR STEAM-GENERATORS.

SPECIFICATION forming part of Letters Patent No. 591,298, dated October 5, 1897.

Application filed June 26, 1897. Serial No. 642,503. (No model.) Patented in France January 30, 1897, No. 263,588.

To all whom it may concern:

Be it known that I, LEON SERPOLLET, of Paris, Republic of France, have invented a new and useful Improvement in Tubes for 5 Steam-Generators, which is fully set forth in the following specification, and for which I have obtained French Patent No. 263,588, dated January 30, 1897.

This invention relates to improvements in 10 the construction of vaporizing-tubes of quasi-capillary internal section and intended to constitute an instantaneous steam-generator or part of such a generator; and it has for 15 object and for result to render such vaporizing-tubes stronger while very much lighter than usual and at the same time to render their manufacture more simple and their shape more regular and more suitable for utilizing the action of the heat given off by the 20 furnace, irrespective of the nature of the said furnace—that is to say, whatever may be the system of heating employed—and irrespec- 25 tive of the regularity or the intermittency of the heating.

25 The improvements consist, after having obtained a flat tube of the desired length and section, the said section being of the plane shape indicated at A in Figure 1 of the accompanying drawings, in filling the said tube 30 with dry fine sand, and then while the sand is confined in twisting the said tube about its longitudinal axis, as shown at B, in such a manner that the ends of the plane section forming the longitudinal edges of the tube 35 shall assume the form and direction of two parallel helices of greater or less pitch, as shown in Fig. 2. This figure shows a short length of the new tube ending at one side of the figure in a screw-threaded tubular union-piece C for engagement with a union-nut, the 40 oblique section taken from the opposite side showing that the helical arrangement will also be assumed by the approximately capillary internal space.

45 The tube thus formed by longitudinal torsion may be left straight, or it may be coiled in the form of a spiral arranged in a single plane, or it may be coiled to form two or more spirals or "stages" wound in the same direction arranged side by side and connected at the

center, as shown in front and side elevation in Figs. 3 and 4, respectively, or it may be bent in zigzag fashion into the form of a flat serpentine coil of several convolutions or branches, as shown in front elevation in Fig. 5, each 55 end terminating in a flanged union or, as shown in the said figure, in a screw-threaded union C, similar to that shown in Fig. 2 and suitable for engagement with a union-nut E, the two unions, one for the entrance of the 60 water or steam and the other for the exit thereof, being situated on the same side, as shown in full lines in Fig. 5, or one on one side and the other on the opposite side, as shown in full and dotted lines, or at another 65 place.

Several tubes coiled in a spiral manner or bent into the shape of flat serpentine coils may be arranged above one another, or coupled together side by side in such a manner 70 as to form series of tubes arranged in stages, or coupled together in sufficient number to allow of the whole of the generator exposing the necessary heating-surface to the furnace-gases. These several tubes are jointed or connected together or to collecting-tubes either 75 by end unions or by connecting-bends, which may be simply cylindrical or may themselves be twisted helically, or by simple tubular union-pieces.

80 In the spiral arrangement when the two end portions D D' of the tube, one for the inlet and the other for the outlet, are placed side by side they are or may be connected together by a collar F, whereby all deformation caused 85 by the pressure which the steam may acquire inside the tube is rendered impossible. The said end portions of the tube may be twisted like the remainder of the tube or be left cylindrical, as shown.

90 The great resistance offered to the internal pressure of the steam by the new form of the vaporizing-tube allows of making the tube with very thin walls, so as to produce a light vaporizing apparatus, while rendering it at 95 the same time suitable for all intermittent heating of suitable intensity, especially for heating effected by means of burners fed with petroleum or any other combustible liquid.

Having now particularly described and as- 100

certained the nature of the said invention and in what manner the same is to be performed, I declare that what I claim is—

A steam-boiler tube, flattened and having an approximately capillary internal space, said tube being twisted so that its longitudinal edges assume the form of two parallel helices, substantially as described.

In testimony whereof I have signed this specification in the presence of two subscribing witnesses.

LEON SERPOLLET.
